UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

EXTENSIBLE HAMMER MECHANISM.

1,253,696.

Specification of Letters Patent. Patented Jan. 15, 1918.

Application filed May 17, 1916. Serial No. 98,018.

To all whom it may concern:

Be it known that I, WILLIAM W. LASKER, a citizen of the United States, residing in Brooklyn, in the county of Kings and State of New York, have invented certain new and useful Improvements in Extensible Hammer Mechanism, of which the following is a specification.

This invention relates to accounting machines in general, and especially to improvements in the type positioning and printing mechanism illustrated in the copending application of James Powers, Serial No. 847,581, filed June 27, 1914.

With mechanism in which swinging type carriers coöperate with type striking hammers, such as illustrated in the aforesaid copending application, demand has long existed for facilitating the assemblage of the several parts. When the several castings of the mechanism were assembled, and the active parts put in place, it was frequently found that but a fraction of a thousandth of an inch departure from perfect alinement would cause any amount of trouble when it was attempted to operatively connect the swinging type carriers with the hammer actuating means.

Experiment has shown that slightly elongating or shortening the lever connecting the type carrier actuators with the hammer actuators was all that was necessary to properly bring the several parts into proper operative relation. To this end the present invention contemplates the provision of an adjustable connecting means for connecting the type carrier actuators with the hammer actuators.

These and other features, capabilities and advantages of the invention will appear from the subjoined detail description of one specific embodiment thereof illustrated in the accompanying drawing, in which—

Figure 1 is a fragmental elevation illustrating a section of an accounting machine equipped with the present improvement showing the hammer lever anchoring the hammers in retracted position.

Fig. 2 is a fragmental elevation illustrating a section of an accounting machine similar to Fig. 1, but showing the hammer lever having released the hammers to permit them to strike type.

Fig. 3 is a detached detail of an extensible lever showing the same in extended position

as distinguished from Figs. 1 and 2, in which the lever is shown in contracted position.

In the embodiment shown there is illustrated a shaft 8 to which the type carrying segments 9, the gear segments 10, and the 60 retractor cheeks 11 are pivotally connected. The segments 9 and 10 are loosely connected to one another by the connection formed by the slot 12 and pin 13.

The segments 9 are provided with the type 65 14 to coöperate with the hammers 15 when the segments 9 are released by the retractor bar 16 of the retractor cheeks 11.

The segments 10 are provided with teeth 70 17 for coöperation with the accumulators 18 to accumulate for the purpose of adding.

The segments 9 are provided with suitable springs (not shown) whereby when the retractor bar 16 is actuated out of contact with the segments 9, such segments 9 will be resiliently advanced to the position determined, either by the accumulating wheels 18 or any other suitable means. The segments 10, due to the connection, slots 12 and pins 13, will be carried forward with the 80 segments 9 when they are released. In turn when the retractor bar 16 is withdrawn to return the segments 9, the rear edges of the segments 9 will engage the stops 19 formed on the segments 10 and thereby simultaneously return the segments 10.

For actuating the retractor cheeks 11 and thereby the retractor bar 16, a lever 20 is provided pivotally connected at its upper end to the shaft 21. The lever 20 comprises 90 essentially an upper arm 22, the upper end of which is pivotally connected as aforesaid to the shaft 21, and a lower enlarged portion 23 in which is formed a heart-shaped cam slot 24. The rear lower portion of the lever 95 20 is pivotally connected to the upwardly extending portion 25 of the link 26, the lower forward end of which link is pivotally connected to the crank sector 27, which is secured to the main actuating shaft 28. One 100 of the retractor cheeks 11 is provided with a cam roller 29 for engaging the cam slot 24. The operation of the foregoing is substantially as follows: the crank sector 27 is oscillated by the shaft 28, the forward oscillation initiating the actuation of the type carrying segments and the rearward oscillation culminating the actuation of the type carrying segments by initiating the withdrawal of the same. By the connection of 110

the link 26 with the lever 20, and the connection of the retractor cheeks 11 with the lever 20 by means of the cam roller 29 co-operating with the cam slot 24, the retractor bar 16 will be actuated on the forward oscillation of the crank sector 27 thereby to release the type carrying segments 9 and permit them to be advanced by springs (not shown, as aforesaid), and in turn on the rearward oscillation of the crank sector 27, the retractor bar 16 will be actuated to engage the segments 9 and return them to idle position thereby likewise returning the gear segments 10, as aforesaid. From the foregoing it will be seen that the final position of the roller 29 on the forward oscillation of the crank sector 27 will be in the forward portion of the cam slot 24 and that the final position of the roller 29 on the rearward oscillation of the crank sector 27 will be in the rearward portion of the cam slot 24, thereby effecting a dwell at both final positions, which dwell is instrumental in facilitating the proper operation of the several parts of the printing and accumulating mechanisms.

Whenever the type carrying segments are released to be positioned for printing, their forward movement will initiate the actuation of the hammers 15. The hammers 15 are pivotally mounted on the shaft 30. The head portion of each hammer 15 is provided with a hook portion 31 to co-operate with a latch 32 pivotally mounted on the shaft 33. Each latch 32 is pivotally connected with a lever 34, the rear end of which rides on the forward end of a link 35 loosely mounted on the shaft 36, the rearward end of which link 35 is provided with a ledge 37 positioned to be engaged by the cam surface 38 of a segment 9 when such segment is advanced into printing position. Whenever a segment 9 is so advanced into printing position and strikes the ledge 37 of a link 35, such link will position the lever 34 riding thereon to be actuated which, in turn, will actuate the latch 32 connected thereto, which latch 32 will thereby be actuated to release the hammer it is anchoring and permit such hammer to be swung upward by its motive spring 39, which motive spring connects the rearwardly extending portion 40 of the hammer 15 with the spring abutment 41. The rearwardly extending portion 40 of each hammer 15 is also provided with a finger portion 42 for engagement by the universal retractor plate 43 common to all of the hammers 15, which retractor plate 43 is fixed to the arms 44 which are preferably fixed to the shaft 30. When the arms 44 are so fixed to the shaft 30, an arm 45 is preferably fixed to the arm 30 in accordance with the present embodiment, which arm 45 is pivotally connected to the crank sector link 26 by the hammer link 46. The construction of this hammer link 46 in relation to the several

parts of the mechanism forms the main feature of the present improvement. The operation of the aforesaid is substantially as follows: whenever the crank sector link 26 is actuated by the forward or initial oscillation of the crank sector 27, thereby permitting the advance of the type carrying segments 9, the link 46 will be actuated forwardly thereby to swing the arm 45 and with it the retractor plate 43 out of the way of the fingers 42 to permit such of the hammers 15 as are released to be swung up to strike types 14. Then upon the return oscillation of the crank sector 27, the link 46 will be actuated rearwardly thereby swinging the retractor plate 43 into contact with the fingers 42 and in its further movement withdraw the hammers 15 until their hook portions 31 are again engaged and anchored by the latches 32.

The present invention contemplates making the lever 46 of two parts, namely, the forward portion 47 and the rearward portion 48. The rearward portion 48 is provided with two set screws 49 and 50, and the forward portion 47 is provided with two slots 51 and 52 for receiving the screws 49 and 50 respectively. By means of the foregoing screw and slot connection, the lever 46 may, with facility, be elongated or shortened to various lengths within certain limits. In Figs. 1 and 2, lever 46 is shown in its extreme shortened form, and in Fig. 3 the lever is shown in its extreme elongated form.

It will be seen that the portion 48 of the lever 46 is provided with a slot 53 for receiving the screw 54 of the link 26, whereby the links 46 and 26 will have a loose connection with one another. For resiliently maintaining the link 46 so that the forward end 105 of its slot 53 engages the screw 54, the spring 55 is provided which connects the link 46 with the link 26.

It is obvious that various changes and modifications may be made to the details of the construction without departing from the general spirit of the invention.

I claim:

1. The combination with swinging type carrying segments and type striking hammers, of a hammer retractor, means for actuating said type carrying segments into printing position, retracting means for permitting the said segments to be actuated, and a longitudinally adjustable link connecting said retracting means with said hammer retractor to permit the hammers to be actuated simultaneously with the actuation of the type carrying segments, the longitudinal adjustment of said link facilitating the adjustment of the several parts of the mechanism when assembling the same.

2. The combination with swinging type carrying segments and type striking hammers, of a hammer retractor, an initial oscil-

- latable actuator, retracting means for said type carrying segments, means for actuating said type carrying segments into printing position, a link connecting said actuator with said retracting means, and a second longitudinally adjustable link connecting said first link with said hammer retractor. 5
3. The combination with swinging type carrying segments and type striking hammers, of a hammer retractor, means for actuating said type carrying segments into printing position, retracting means for permitting the said segments to be actuated, a longitudinally adjustable link connecting said retracting means with said hammer retractor to permit the hammers to be actuated simultaneously with the actuation of the type carrying segments, the link comprising two portions, and set screws for connecting the two portions to one another. 10
4. The combination with swinging type carrying segments and type striking hammers, of a hammer retractor, an initial oscillatable actuator, retracting means for said type carrying segments, means for actuating said type carrying segments into printing position, a link connecting said actuator with said retracting means, a second longitudinally adjustable link connecting said first link with said hammer retractor, the second link comprising two portions, set screws secured to one of said portions, and there being slots in the other of said portions for receiving said set screws whereby 25 the portions may be anchored to one another to form different lengths of said second link. 30
5. The combination with swinging type carrying segments and type striking hammers, of a hammer retractor plate, a shaft, arms mounting said retractor plate and fixed to said shaft, means for actuating said type carrying segments into printing position, retracting means for said type carrying segments, a lever secured to said shaft, and a longitudinally adjustable link connecting said lever with said retracting means to permit the hammers to be actuated simultaneously with the actuation of the type carrying segments. 40
6. The combination with swinging type carrying segments and type striking hammers, of a hammer retractor plate, a shaft, arms mounting said retractor plate and fixed to said shaft, means for actuating said type carrying segments into printing position, retracting means for said type carrying segments, a lever secured to said shaft, a second shaft, a second lever pivotally connected to said second shaft, an enlargement 45 at the lower end of said second lever having a heart-shaped cam slot therein, a roller on 50
- said retracting means engaging said cam slot, an initial oscillatable actuator, a link connecting said second lever with said actuator, and a second link longitudinally adjustable and connecting said first named lever with said first named link. 55
7. The combination with swinging type carrying segments and type striking hammers, of a hammer retractor plate, a shaft, arms mounting said retractor plate and fixed to said shaft, means for actuating said type carrying segments into printing position, retracting means for said type carrying segments, a lever secured to said shaft, a second shaft, a second lever pivotally connected to said second shaft, an enlargement at the lower end of said second lever having a heart-shaped cam slot therein, a roller on 60 said retracting means engaging said cam slot, an initial oscillatable actuator, a link connecting said second lever with said actuator, a set screw on said link, a second link longitudinally adjustable having an elongated slot receiving said screw and forming 65 a loose connection between said first named link and said second link, the second link connecting said first named link with said first named lever. 70
8. The combination, with type carrying segments and type striking hammers, of a hammer retractor; an actuator; retracting means for said segments; means for actuating the segments into printing position; a link connecting the actuator with the retracting means; and an extensible link connecting said first named link with the hammer retractor and comprising two portions, one of which has aligned slots at its inner end, and set screws passing through said 75 slots respectively and screwed into the inner end of the other portion. 80
9. The combination, with type carrying segments and type striking hammers, of a hammer retractor; an actuator; retracting means for said segments; means for actuating the segments into printing position; a link connecting the actuator with the retracting means; and an extensible link connecting said first named link with the hammer retractor and comprising two portions, one of which has aligned slots at its inner end, and set screws passing through said slots respectively and screwed into the inner end of the other portion, one of said slots having 85 an open end for facilitating the assembling of the link. 90
